CLAIM

The ornamental design of an interlocking component for interconnecting the side panels of a collapsible container, as shown.

DESCRIPTION

FIG. 1 is a perspective view from above and from one end of an interlocking component showing the new design;

FIG. 2 is a cross-sectional end elevation of the edge component of FIG. 1, and

FIG. 3 is a perspective view from beneath and from the other end of the edge component of FIG. 1.

FIG. 1.FIG. 2.FIG. 3.
